UNITED STATES PATENT OFFICE.

WALDEMAR KOPS, OF NEW YORK, N. Y., ASSIGNOR TO KOPS BROTHERS, OF NEW YORK,
N. Y., A FIRM.

BRASSIÈRE.

1,237,059.

Specification of Letters Patent. Patented Aug. 14, 1917.

Application filed March 7, 1917. Serial No. 152,991.

To all whom it may concern:

Be it known that I, WALDEMAR KOPS, a citizen of the United States, residing in the borough of Manhattan, city, county, and 5 State of New York, have invented an Improvement in Brassières, of which the following is a specification.

I am aware that the use of brassières or corset covers is now, and for some time past 10 has been more or less general, and consequently articles of this kind by themselves are not new. I am aware also, that heretofore various forms of bust supporters have also been used, including a bust supporter 15 so constructed as to be adjustable to position on the body of the wearer. In the case of the brassière a separate garment is used, as is also the fact with the bust supporters, and consequently, when either a bust sup- 20 porter or a corset was used together with the brassière, there was the necessity of placing and adjusting two garments to position on the body. Furthermore, in many of the bust supporters heretofore employed, more 25 particularly to the one to which I have referred, the adjusting devices are such as to be readily observed through a thin waist or other outer garment when no brassière was used between the two, making it necessary 30 consequently, to employ a brassière or extra garment between the bust supporter and the outer garment if the adjusting devices of the bust supporter were to be unobserved.

The object of my present invention is to 35 overcome the hereinbefore named disadvantages in the use of bust supporters and brassières, by combining with a brassière a bust supporter so constructed as to be adjustable to position within the same as will be here- 40 inafter more particularly described.

In the drawing:

Figure 1 is an elevation of the inner side of a brassière and bust supporter made in accordance with my present invention.

45 Fig. 2 is an elevation showing the application of the same when in use on the body.

Referring to the drawing, it will be seen that in carrying out my invention the brassière consists of a member made of any suitable fabric or lace, or both, which may be made in halves as indicated at 10 and 11, the halves being secured together at the back or rear of the garment along a line of sewing, indicated at 12. The front edge of 50 55 the one half 10 may be provided with but-

tons 13 and the front edge of the other half 11 with button holes 14 by means of which the front edges of the garment may be connected when in position for use. The brassière as is also customary may be provided in each half thereof with shoulder straps 15 and 16. While I have herein shown and described the body of the brassière as made in halves, it will be understood that it may be made from a single piece of material or divided into any desired number of parts.

In each half of the brassière as illustrated, I employ a suitable bust form so secured therein as to be adjustable to position on the body of the wearer. In the brassière 70 body half 10, an anchor strap 17 is secured along substantially the axillary line or that extending longitudinally of the body immediately below the arm pit. This anchor strap may be secured to the inner side of this half of the brassière in any suitable manner, and so as to have one edge thereof free from the garment in which edge there is a series of eyelets 18. In this half of the brassière there is a bust form indicated at 19. This, 75 as will be understood, may be made of any suitable material, although in order to more closely conform to the body of the wearer, I prefer to make it of elastic fabric. At the inner end of the bust form 19 the same is 80 provided with a strap 20 in which in suitably spaced positions the corresponding ends of the laces 21 are secured. Each of these laces is threaded through one of the eyelets 18 in the anchor strap and the other 85 ends of the laces are brought together and secured in a junction strap indicated at 22 to which is also secured a tape 23. This tape 23 as illustrated, may be passed through a tape hole provided therefor in a tab 24. 90 The opposite or front edge of the bust form is provided with a front strap 25 along which in suitable positions there are secured eyes 26.

Similarly in the other half of the brassière body there is an anchor strap 27 fixed therein substantially in the other axillary line and provided along its free edge with a series of eyelets 28. In this half of the brassière body there is a bust form 29, similar 100 in all respects to the bust form 19 and therefore fitted along its inner or rear edge with a strap 30 to which in suitable positions the corresponding ends of laces 31 are fixed. Each of these laces 31 is threaded through 105 110
